TELEPRINTER CABINET

Robert O. Carlson, Arlington Heights, Ill., assignor to
SCM Corporation, New York, N.Y., a corporation of
New York

Filed May 22, 1968, Ser. No. 12,045

Term of patent 14 years

Int. Cl. D18—03

U.S. Cl. D64—11

FIGURE 1 is a perspective view of the teleprinter cabinet of the invention, showing my new design;

FIGURE 2 is a front elevational view of the teleprinter cabinet shown in FIGURE 1;

FIGURE 3 is a rear elevational view of the teleprinter cabinet shown in FIGURES 1 and 2; and

FIGURE 4 is a left-side elevational view of the teleprinter cabinet as viewed in FIGURES 1 and 2.

The essential features of my design reside in the portions shown in solid lines, conventional keys and other elements being shown in broken lines for illustrative purposes.

I claim:

The ornamental design for a teleprinter cabinet, substantially as shown and described.
